Fig. 14.

Fig. 13.

FIG. 1 is a side elevational view of a shelter showing my new design, the other three sides being identical to the side shown;

FIG. 2 is a perspective view as seen from above;

FIG. 3 is a perspective view as seen from below;

FIG. 4 is a top plan view;

FIG. 5 is a bottom plan view;

FIG. 6 is an enlarged fragmentary top plan view showing the central portion of the shelter as illustrated in FIG. 1;

FIG. 7 is an enlarged fragmentary plan view showing the middle portion of the lower margin thereof;

FIG. 8 is an enlarged fragmentary top plan view showing the central portion of the lower right hand quarter thereof;

FIG. 9 is an enlarged fragmentary top plan view showing the lower right hand corner portion thereof;

FIG. 10 is an enlarged fragmentary sectional view, taken along the line 10—10 of FIG. 4;

FIG. 11 is an enlarged fragmentary sectional view, taken along the line 11—11 of FIG. 4;

FIG. 12 is an enlarged fragmentary sectional view, taken along the line 12—12 of FIG. 4;

FIG. 13 is an enlarged fragmentary sectional view, taken along the line 13—13 of FIG. 4; and

FIG. 14 is an enlarged fragmentary elevational view of one corner, the other three corners being identical to the corner shown.

I claim:

The ornamental design for a shelter, substantially as shown and described.
